(57) **CLAIM**

The ornamental design for a vehicle tire shaped fluid container, as shown and described.

DESCRIPTION

FIG. 1 is a front perspective view of a vehicle tire shaped fluid container, showing my new design, with a cap in place; FIG. 2 is a front perspective view of the vehicle tire shaped fluid container as in FIG. 1, showing my new design, with the cap removed;

FIG. 3 is a left side elevation view thereof, the right side elevation view being a mirror image thereof; and,

FIG. 4 is a rear perspective view, shown standing upon an optional base at 90 degrees to the position shown in FIGS. 1 to 3.

The optional trapezoidal base portion, with a logo thereon, shown in dashed phantom lines in FIGS. 1 to 4 is shown for environmental purposes only and forms no part of the claimed design.

The optional bar handle portion shown in dashed phantom lines in FIG. 4 is shown for environmental purposes only and forms no part of the claimed design.
